Primary Examiner—Jeffrey Asch**CLAIM**

The ornamental design for the compact disc rack, as shown and described.

DESCRIPTION

FIG. 1 is a front elevational view of the compact disc rack showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a left side elevational view with the legs shown in a folded or closed condition.

FIG. 8 is a front elevational view of an alternative embodiment thereof;

FIG. 9 is a rear elevational view thereof;

FIG. 10 is a left side elevational view thereof;

FIG. 11 is a right side elevational view thereof;

FIG. 12 is a top plan view thereof;

FIG. 13 is a bottom plan view thereof; and,

FIG. 14 is a left side elevational view with the legs shown in a folded or closed condition.
